Primary Examiner — T. Chase Nelson*Assistant Examiner* — Mark Cavanna(74) *Attorney, Agent, or Firm* — Eric T. Addington; James Vago**(57) CLAIM**

The ornamental design for skin analyzing device, as shown and described.

DESCRIPTION

FIG. 1 is a perspective view of skin analyzing device, embodying our new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom view thereof.

The broken lines shown are included for the purpose of illustrating portions of the skin analyzing device that form no part of the claimed design.
